CIGAR BUNCH CUTTING MECHANISM

Lester Ferenci, Brooklyn, N. Y., assignor to International Cigar Machinery Company, a corporation of New Jersey

Original application January 2, 1937, Serial No. 118,810. Divided and this application December 12, 1940, Serial No. 369,781.

5 Claims. (Cl. 146—151)

This invention relates to cigar bunch machines, more particularly to long filler feeds for the same. Its main object is to obtain uniformity in the density of the bunches produced.

The stream of tobacco formed by placing the stemmed leaves in the feed channel of the bunch machine by the attendant is limited by the vertical belts forming the sides of the channel and hence is constant in width and variable in height, depending on the number of layers of leaves placed therein. Therefore by superposing the individual bunch lengths cut from this stream in a vertical column, instead of side by side in a horizontal column as heretofore, a tobacco mass of constant cross-section is obtained from which the bunch charges are separated, and thus greater uniformity of the bunches produced by the machine is attained. Moreover, in case the width of the filler stream is greater than the desired width of bunch charges, the separated bunch lengths may be compressed to the required width before being superposed.

To this end, the individual bunch lengths are transferred directly from the filler feed, wherein they are cut, to a vertical column either at the top or bottom thereof, and a bunch charge of predetermined volume and customary thickness is separated from the column after the same has been compacted vertically. The filler feed may be of any suitable type.

In the accompanying drawings which form a part of this specification and in which like characters of reference indicate the same or like parts:

Fig. 1 is a side elevation of a cigar bunch machine embodying my invention; and

Fig. 2 is a detail view on line 2—2 of Fig. 1.

The stream of tobacco T is advanced on to a tilting platform 17 when the same is in its upper position 17', shown in dotted lines in Fig. 1, at the outer end of a discharge chamber formed by stationary side walls 16, 18' and a bottom plate (not shown) aligned with the channel formed by bolts (not shown). The platform 17 is mounted on an arm 20 pivoted on a shaft 21 supported by the frame 22 of the machine. The arm 20 is connected by a rod 23 with a lever 24 fulcrumed on a shaft 25 and having a roller 26 held against a plate cam 27 on cam shaft 28 by a spring 29 anchored to the frame of the machine and connected to the arm 20.

While the feed belts are stopped, a clamp arm 30 pivoted on shaft 21 and actuated by a cam lever 31 connected to arm 30 by a rod 32, descends upon the stream of tobacco T previously

advanced on platform 17 and holds it in place while a corrugated cutter 33 severs a bunch length T'. The configuration of the cutter is such that it will trim the end of the severed bunch length to the shape suiting the particular taper of the cigar bunch end and the adjacent end of the next bunch length is simultaneously shaped, as is well known in the art. The underlying edge of the platform has a portion which is cut away to conform to the configuration of the knife. The lever 31 is actuated by an arm 34 fast on its fulcrum shaft 35 and carrying a roller 36 held against a plate cam 37 on shaft 28 by a tension spring 38 having one end fastened on shaft 21 and its other end engaging the arm 30. The cutter 33 is adjustably fastened in a holder 39 attached to a slide 40 reciprocating in frame 22, the said slide having a trunnion 41 engaging a lever 42 fulcrumed on shaft 25 and provided with a roller 43 in engagement with a cam track 44 in the rear surface of cam 45.

After severance of the bunch length T', the platform 17 is swung by the lever 24 into its lower position shown in full lines, and the arm 30 is similarly actuated by its cam lever 32, whereupon a rake 46 resting on the platform and swinging on a pivot 47 on the end of an arm 48 pushes the charge T' into position T'' on a forked plate 49. The arm 48 is actuated by a cam lever 50 fast on its fulcrum shaft 51 and carrying a roller 52 held against a plate cam 53 on shaft 28 by an adjustable weight carried by a rod 54 fast on shaft 51. If desired the width of the filler stream may exceed the width of the bunch charges and the rake 46 may be actuated to compress the bunch lengths to the desired width. By virtue of this arrangement a thinner stream of filler tobacco may be utilized, wherefore the attendant may build up the filler stream more rapidly and run the machine at a higher speed.

Following the ejection of the bunch length T'', the platform 17, clamp arm 30 and rake 46 return to their initial positions 17', 30' and 46', respectively, shown in dotted lines. The cam shaft 28 has a sprocket 55 continuously driven by a chain 56 from a sprocket 57 on the drive shaft 58, which is driven from the main drive of the machine by a sprocket 59 and chain 60, connected to the main drive of the machine.

The prongs of plate 49 project through slots in the side walls of the vertical chamber 61, as shown in Fig. 1, and the plate is fastened to a block 62 attached to horizontal rods 63 slidable in a member 64 carried by parallel links 64',

and 65, 65' pivoted on a bracket 66 attached to frame 22 and assuring a parallel up and down motion to member 63. The slots in the side walls of chamber 16, for the reception of the prongs of plate 49, extend only partially from the top of the chamber, the lower portion of the same being left solid. To arm 64 is attached a rod 67 connecting the same with a cam lever 68 which has a roller 69 held against a plate cam 70 by a spring 71. On the block 61 is pivoted a link 72 which is connected to a stud 73 on a bell crank lever 74 fulcrumed on shaft 21, the lever 72 being actuated by a cam-operated rod 75 from a cam (not shown).

The plate 49 after having received the bunch length T" is normally depressed into its lowermost position by the descent of rod 67 and is then slid out of chamber 16 by the action of rod 75 on lever 74 which pulls the lever 72 from position 72' to position 72''. The subsequent ascent of rod 67 raises plate 49 back to its normal level, and the ascent of rod 75 restores the same to its receiving position on that level.

Upon retraction of the plate 49, the bunch length T", if the chamber 16 has not been filled as hereinafter described, drops upon a slotted plate 76 which forms the bottom of a horizontal chamber 77 below the open vertical chamber 16. Adjacent the bottom of chamber 16 is mounted a horizontal knife blade 78 attached to a plate 79 which is vibrated or reciprocated longitudinally with the knife blade by a connecting rod 80 attached to the plate by a pin fastened to the plate and connected to a crank 81 rotated by a shaft 82 driven by gears 83 from a shaft 84. An arm 85 linked to a rod 86 actuated by a cam lever 87 is fastened to a sleeve 88 in which the shaft 82 turns, the sleeve being supported by a stand 89 fastened to the bed of frame 22, and carries the head 90 whereon the plate 79 is slidably mounted. Since the aforesaid crank 85 is clamped to sleeve 88, it swings the entire unit laterally to and fro. Behind the knife 78, in the horizontal plane of its rotation, is a segmental follower plate 91 mounted on support 90.

The knife 78 separates a bunch charge B from the column T" and the thickness of the stream of tobacco whence the bunch lengths are severed, is maintained by the attendant to supply bunch lengths having a greater quantity of tobacco than required for one bunch. The separated bunch charge is then pushed by a plunger 92 into a movable charge transfer 93, of well known construction, such, for instance, as shown in Patent No. 1,838,192, issued December 29, 1931 to R. E. Rundell, which delivers the same to the rolling apron 94. The plate 91, which partakes of the swinging motion of the knife 78 but not of its reciprocating motion, supports the tobacco column in chamber 16 after the bunch charge B has been cut and until the plunger 92 has delivered the bunch charge to the charge transfer and returned to its starting position. At this time the plate 91 and the chamber 77 maintain the separated bunch in compacted condition while it is advanced into the charge transfer. The plunger 92 has an arm passing through the slot in plate 76 and attached to a slide 95 mounted on a pair of rods 96 supported by a standard 89, and the slide 95 is moved into position 95' to push the bunch charge into the charge transfer and then back, by a cam-operated lever 97.

The surplus tobacco from bunch length T", after the return of plunger 92 and knife 78 into

their starting positions, drops on plate 76 and is augmented by the next bunch length and brought down by plate 49, the accumulation of these surpluses causing the height of the tobacco column in chamber 16 to gradually rise. When the height of this column has risen above the unslotted portion of chamber 16, the plate 49 can no longer descend to the bottom but stops when it has compacted the tobacco column to a density determined by the tension of spring 71, the remainder of the stroke of lever 68 being absorbed by the stretching of the spring 71 which permits the roller 69 to be lifted off cam 70. In practical operation, the blade 78 and plunger 92 are preferably not set into action until the plate 49 has delivered enough bunch lengths to fill the unslotted portion of chamber 16, so that the first bunch charge actually used for production is separated from a compacted tobacco column.

20 When the height of the tobacco column in chamber 16 is low, an adjustable stop screw 98 carried by an arm 99 fast on the fulcrum shaft 100 of the arms 64 and 64' engages with a detent or latch 101 fulcrumed on a stud 102. This latch is urged by a spring 103 into a position wherein it retains a curved arm 104 pivoted on a stud 105, in its normal position shown. To the arm 104 is fastened a semi-circular cam piece 106 on which rides a roller 107 carried by a pawl 108 pivoted on an arm 109 loosely mounted on a shaft 110, thereby normally holding the pawl away from a ratchet 111 fixedly mounted on the shaft 110 against the tension of a leaf spring 112 bearing against the pawl 108 and anchored to arm 109 (Fig. 1). The shaft 110 carries a bevel gear 113 which drives a bevel gear 114 on the shaft 15 which controls the feed of tobacco T as heretofore described.

On the arm 109 is pivoted a link 115 provided with a slot receiving a pin 116 of a crank 117 fastened on drive shaft 58, the slot being elongated sufficiently to provide lost motion of the link so that the arm 109 may be vibrated at the desired intervals.

45 45 When the detent 101 is tripped by the screw 98, the arm 104 is pulled by a spring 118 against a stop 119, thereby turning the cam piece 106 into the dotted position whereupon the spring 112 presses the pawl 108 into engagement with 50 the ratchet 111 which thus partakes of the next forward stroke of arm 109. The turning of ratchet 111 causes the shaft 110 to transmit motion to countershaft 15 which in turn rotates the sprocket 14 which drives the feed belts (not shown).

But when the column in chamber 16 has risen beyond a certain predetermined height, which in the present embodiment of the invention corresponds to the height of the unslotted portion 60 of the chamber, the downward motion of plate 49 is stopped by the column before the screw 98 trips the lever 101. The pawl 108 therefore remains in its ineffective position and no tobacco is fed during that cycle of the machine. The platform 17 then descends empty and no additional tobacco is delivered to chamber 16 until the height of the column has fallen below the critical height upon removal of the required number of bunch charges to the charge transfer. 65 The screw 98 is so adjusted that the tripping height of the column is somewhat more than one charge-height above the lowermost possible position of plate 49, so that the minimum height of the column upon charge removal following a feedless cycle will remain above the unslotted

portion of the chamber and the column will be subjected to the pressure of plate 49. This pressure, which is regulated by adjusting the tension of spring 71, controls the tobacco density in chamber 77 after the lower portion of chamber 16 has been filled to the tripping height, so that bunch charges B of uniform density are obtained by this arrangement.

The inner face of cam piece 106 is provided with a raised portion 120 engageable with a finger 121 pivoted on arm 109 and held against a stop therein by a spring 123. During the forward motion of arm 109 the finger 121 by virtue of the yielding of spring 123 passes under the projection 120, but on its backward motion is maintained in engagement with the projection by the stop 122, and thus raises the cam piece into pawl-lifting position, thereby resetting the trip lever 101 which then is ready for the next cycle.

The charge transfer 93, which is controlled by suitable mechanism 124 of well known type, for up-and-down motion, and by mechanism 125 of conventional construction, for swinging the same around its horizontal axis, delivers the bunch charge B into the loop of the rolling apron 94 attached to a table 126 on which the same is rolled within a binder by a rolling pin 127 in a well known manner, to form a bunch. The named mechanisms are automatically operated in synchronism with the feed mechanism herein described.

As stated above, each bunch length T' delivered by the tobacco feed should contain at least as much tobacco as is required for one bunch charge B. For high speed operation, this ratio can be increased to two or more times this quantity, so that the feed belts will operate intermittently every second bunch, thereby affording the operator more time for feeding. While the invention has been described in connection with the production of long filler cigar bunches, it will be understood that it is applicable to scrap bunch cigar machines.

This application constitutes the division of my co-pending application, Serial Number 118,810, filed January 2, 1937, on which Patent No. 2,255,051 was issued September 9, 1941.

What is claimed is:

1. In a cigar machine, the combination with members for supporting a vertical column of laminated cigar bunch lengths having corrugated ends, of means for compacting said column vertically to a predetermined density, a horizontal cutter adapted to sever said column horizontally to separate a bunch charge therefrom, mechanism for advancing said cutter horizontally through said column lengthwise of the laminated bunch lengths to sever a bunch charge, means for vibrating said knife horizontally while it is being advanced through said column, and mechanism for transporting the severed charge to bunch rolling position.

2. In a cigar machine having mechanism for severing cigar bunch lengths of tobacco having corrugated ends from a stream of long filler to- 65

- bacco and superimposing the severed bunch lengths to form a vertical column of tobacco, the combination with members coacting to compact said column vertically to a predetermined density, a horizontal cutter having a cutting edge provided with a straight portion extending obliquely relative to the column and adapted to engage a corner of the column and then traverse the lower end of the compacted column and thereby separate a bunch charge from the column, a horizontal plate arranged behind said cutter and horizontally aligned with the cutter to enter between the severed charge and the remainder of the column, and mechanism for simultaneously moving said cutter and plate edgewise horizontally through the column to cause said cutter to separate a bunch charge from the column and advance said plate between the separated bunch charge and the remainder of the column and maintain said plate in a position supporting the remainder of the column.
3. In a cigar machine having mechanism for severing cigar bunch lengths having corrugated ends from a stream of long filler tobacco and superimposing them to form a vertical column of tobacco, the combination with means for compacting said column vertically, of a support, means for moving said support horizontally, a horizontal knife having a cutting edge extending obliquely of said column and mounted on said support in position to traverse the column when said support is moved horizontally and thereby sever a charge from the column, and means for transferring the severed charge to bunch rolling position following the separation of a charge from the column by said knife.
4. In a cigar machine, the combination with means for compacting a supply of tobacco, of a cutter adapted to separate a charge from the compacted supply of tobacco, means for moving said knife edgewise transversely of its length through the compacted supply of tobacco to separate a charge therefrom, mechanism for imparting a straight line motion to said knife in a direction which is lengthwise of the knife while it is traversing the column, and means for transferring the charge to bunch length position following the separation of a charge from the tobacco supply by said knife.
5. In a cigar machine, the combination with means for compacting a vertical column of tobacco consisting of laminated bunch lengths having corrugated ends, of a cutter provided with a cutting edge having a straight portion extending obliquely of the column and adapted to be moved edgewise horizontally into engagement with one corner of the column and then through the remainder of the column to separate a charge therefrom, a member on which said knife is supported, means for moving said member to cause said knife to traverse the compacted tobacco column horizontally and sever a bunch charge therefrom.

LESTER FERENCI.
